(57) **CLAIM**

The ornamental design for a modular cabinet, as shown and described.

DESCRIPTION

FIG. 1 is a left front perspective view of the design of the modular cabinet;

FIG. 2 is a front elevational view thereof. The ornamental design is not visible in a top plan view or bottom view; FIG. 3 is a right elevational view thereof. The left side is identical to the right side shown in this FIG. 3; and, FIG. 4 is a rear elevational view thereof.

The characteristic feature of the ornamental design resides in the use of a pattern on the doors of a modular cabinet having wheels.

Those portions of modular cabinet in broken lines, specifically the surfaces of the modular cabinet at the top and bottom edges of the doors and surfaces extending back from the doors including other surfaces of the modular cabinet are for illustrative purposes and are not part of the claimed invention.
